UNITED STATES PATENT OFFICE.

WILBRA W. SWETT, OF SPRINGFIELD, ILLINOIS.

PERMUTATION-LOCK.

SPECIFICATION forming part of Letters Patent No. 269,137, dated December 12, 1882.

Application filed April 25, 1882. (Model.)

To all whom it may concern:

Be it known that I, WILBRA W. SWETT, of Springfield, in the county of Sangamon and State of Illinois, have invented a new and Improved Permutation-Lock; and I do hereby declare that the following is a full, clear, and exact description of the same, reference being had to the accompanying drawings, forming part of this specification, in which—

10 Figure 1 is a rear view of my improved lock as applied to a safe-door, with the plate removed. Fig. 2 is a horizontal section on line $\alpha\alpha$, Fig. 1. Figs. 3 and 4 are detail views.

This invention relates to that class of locks 15 which are known as "combination" and "permutation" locks; and it consists mainly in such an adaptation and arrangement of parts as to render the lock capable of being operated by the sense of feeling instead of the sense of sight.

It consists, further, in certain details of construction which, in connection with the foregoing, will be fully described hereinafter.

In the drawings, A represents the door of a 25 safe or other case or box to which the lock is applied, which is provided with a recess adapted to receive the lock, as shown, which recess, being a portion of a true circle, may be readily made by a bit or other boring-tool.

30 B represents the case of the lock, which is provided upon its straight side with a proper opening for the projection of the bolt, and also upon its interior with a stop-block, b, and a central hollow stud, b', as shown.

35 C represents the bolt, consisting of a plate of proper size and shape, having at one end a rectangular portion, c, adapted to project from the lock to engage with the keeper, and at the other a tapering portion, c', having a central 40 slot, c'', adapted to permit the bolt-plate to have its proper movement without interference with the central stud, b'.

D represents a locking-arm pivoted upon the bolt-plate, which is provided with the 45 broad head d, having the projecting tooth d', as shown.

E represents a spring, which is adapted to actuate the locking-arm at the proper time, as will be fully described hereinafter.

50 F represents a tumbler-disk located on the central stud, b', which is provided with the notch f and adjustable pin f', as shown.

G represents a tumbler-disk located on the central stud, b', which is provided with the notch g and the pins g' g'', one on each side, as 55 shown.

H represents a tumbler-disk having the central shaft, h, adapted to extend through the hollow stud b', which is provided with a notch, h', an adjustable pin, h'', upon its inner face, 60 and a series of radial grooves, h³, upon its outer face, as shown. h⁵ represents a knob-handle which is rigidly secured to the shaft h, upon the outside of the door, in any proper manner. Suitable washers are interposed between the tumbler-disks and the bearing-surfaces with which they come in contact. 65

I represents a flat spring extending across the outer face of the disk H, and secured at its ends to the case, which is provided with a detent or tooth, i, adapted to engage with the radial grooves h³, as shown. In the arrangement shown two of the radial grooves are arranged close together and the others of the series farther apart. The two grooves lying 70 together furnish a base-point from which the necessary deductions may be made. When the bolt is in its projected position the end of the spring locking-bar D lies in front of the stop-block b of the case, it being held in this 75 position by the uncut portions of the peripheries of the tumbler-disks bearing against the tooth d' of the locking-bar, as shown.

The operation is substantially as follows: The knob-handle, after having been turned to 80 the right several times in order to bring the tumbler-disks into the proper relation to each other, is moved to the base-point—that is, in such manner as to bring the double groove of the disk H into contact with the detent of the 85 spring I. Having found the base-point by feeling the click as it snaps into the grooves, the grooves are counted in alternate directions until each tumbler in its turn, beginning with the inner one, is brought into the proper position for unlocking. The end of the locking-bar being thus disengaged from the stop-block, 90 the bolt may be moved into the case to unlock the door. 95

By a proper arrangement of the pins any 100 desired combination may be obtained in the manner well understood.

The special advantage of this peculiar construction is that the proper movements to un-

lock the door are obtained through the sense of feeling instead of the sense of sight, the engagement of the detent of the spring I with each groove furnishing a positive indication of 5 a precise point, thus preventing the probability of revolving the disks too far.

Having thus described my invention, what I claim as new is—

In a permutation-lock, the combination of

the disk H, having grooves h^3 , and a detent-spring, I, with a handle or knob, h^5 , for the purpose of arranging the position of the tumbler-disks by feeling said detent snap into said grooves, as shown and described.

WILBRA WENTWORTH SWETT.
